(57) **CLAIM**

The ornamental design for a barrier cover, as shown and described.

DESCRIPTION

FIG. 1 is a perspective view of a barrier cover; FIG. 2 is a front elevation view or a rear elevation view thereof;

FIG. 3 is a right side elevation view or a left side elevation view thereof;

FIG. 4 is a top plan view thereof;

FIG. 5 is a bottom plan view thereof; and,

FIG. 6 is a perspective environmental view thereof positioned on a barrier.

The broken line showing of a barrier is included for the purpose of illustrating portions of the "article" and forms no part of the claimed design.
